SANITARY BUTTER DISPENSER

Henry E. Young and George V. Farnham, Knoxville, Tenn., assignors, by mesne assignments, of forty-two and one-half per cent to said Young, forty-two and one-half per cent to said Farnham, four per cent to Robert Edward Anderson, four per cent to Boyd W. Cox, two per cent to Neal B. Spahr, all of Knoxville, Tenn., and five per cent to Bernard R. Waller and Helen F. Hayes, jointly

Application July 17, 1950, Serial No. 174,320

5 Claims. (Cl. 31—21)

1

This invention relates to the class of cooking utensils, and more particularly to an apparatus for dispensing butter in small pats for serving on a table, and is an improvement over Patent No. 2,553,621, issued May 22, 1951.

An object of this invention is to provide a butter cutter having a cylindrical casing into which a plurality of oblong rectangular sections of butter may be placed and by a simple manipulation of the plunger a pat of butter will be cut from each of the sticks of butter in successive order so that they may be deposited upon a butter tray.

A further object of this invention is to provide a device which will deliver a great number of butter pats in a desired shape without necessitating unsanitary handling thereof as will happen when handled in the usual manner in commercial eating establishments, hotels and restaurants.

Yet another object of this invention is to provide means for keeping the butter sticks used in the invention chilled so that they will slice easily in order to deliver pats with sharp outlines so as to enhance their appetizing appearance.

A still further object of the invention is to provide a device of the type disclosed which may be easily disassembled for washing and cleaning so as to preserve the device in a sanitary condition.

Still further objects of the invention reside in the provision of a butter dispensing device that is strong, durable, convenient in operation, simple in construction and manufacture, pleasing in appearance and quite inexpensive to manufacture.

These, together with the various ancillary objects of the invention which will become apparent as the following description proceeds are attained by this sanitary butter dispenser, a preferred embodiment of which has been illustrated in the accompanying drawings, by way of example only, wherein:

Figure 1 is an elevational view of the sanitary butter dispenser;

Figure 2 is an enlarged vertical sectional view as taken along the plane of line 2—2 in Figure 1;

Figure 3 is a horizontal sectional view taken along the plane of line 3—3 in Figure 2;

Figure 4 is a horizontal sectional view as taken along the plane of line 4—4 in Figure 2;

Figure 5 is an enlarged sectional detail showing the operating mechanism forming one part of the present invention;

Figure 6 is a horizontal sectional detail as

2

taken along the plane of line 6—6 in Figure 5;

Figure 7 is an enlarged sectional detail showing the manner in which the butter-cutting wire is secured to the upper plate of the base; and

Figure 8 is a detail view showing the manner in which the upper plate of the base is secured to the other portions thereof.

With continuing reference to the accompanying drawings, wherein like reference numerals designate similar parts throughout the various views, the reference numeral 10 generally designates a base which is cylindrical in shape and which has an upper plate 12 secured thereon and held by means of screws 14 which are secured in the cover 12 and which are adapted to engage within slots 16 formed in the cylindrical base member 10 so as to form a bayonet connection between the two elements. Positioned on the upper plate 12 of the base 10 is a cylindrical casing 18 and an inner casing 19 for reception of ice, the casing member 18 which has a base plate 20 having a plurality of openings therethrough as indicated at 22 about which upwardly extending flanges 24 are positioned in order that retaining walls 26 may be secured thereto in order that butter chutes 28 may be removably positioned therein.

The chutes 28 are adapted to receive rectangular slabs or sticks of butter 30 and the cover members 32 of the chutes 28 have eyes 34 attached thereto from which weights 36 are suspended by means of suitable chains or strings, as indicated at 38. The casing 18 is provided with a detachably mounted upper cover 40.

Formed in the upper plate 12 of the base 10 is a suitable aperture 42 which is adapted to become aligned with the openings 22 in the bottom plate 20 of the casing 18 upon rotation of the casing 18. Positioned below the upper plate 12 is an L-shaped bracket 44. The bracket 44 is provided with a slot 46 for reception of a bolt and nut member 48 which is adapted to support and adjust platform 50 at a given height so that when one of the sticks of butter comes to rest on the platform 50, a pat of butter will be cut of the height equal to the distance between the wire cutting member 52 which is supported by lugs 54 struck from the plate 12 and the platform 50.

Slidably supported in guides 56 depending from the upper plate 12 is a plunger 58 which has attached thereto a bracket member 60 having a supporting plate 62 for removably receiving a butter tray 64 on which the pat of butter cut by the wire cutter 52 can be deposited. The

plunger 58 is also provided with an upwardly extending pin or screw 66 which is adapted to become engaged within the slot 68 in the ratchet arm 70, which ratchet arm is pivotally mounted relative to the sprocket wheel 72, which sprocket wheel 72 is secured by means of key 74 to a shaft 76 as at 78 to the lower plate 20 of the casing 18. Pivotally mounted on the ratchet arm 70 by means of pin 80 is a ratchet detent 82 which is spring-pressed by coil spring 84 and held into engagement with the teeth of the ratchet wheel 72. Hence, upon actuation of the plunger 58 the ratchet wheel 72 will be rotated, thus rotating the entire casing 18 and the attached butter chutes in the casing so as to urge a different one of the butter chutes to permit its stick of butter 30 to pass through the opening 42 in the base plate 10 so as to drop onto the platform 50 for subsequent engagement with the wire cutter 52. Withdrawal of the plunger 58 permits engagement of the detent 82 with a subsequent tooth of the ratchet wheel 72, and thus pats of butter are cut from successive sticks of butter.

Supporting the ratchet wheel 72 is a tubular member 86 which has secured thereto cruciform braces 88 and 90 which are attached to the sides of the base 10. Downwardly extending from the braces 88 and 90 are suction cups 92 or any other suitable resilient support.

Since, from the foregoing, the construction and advantages of this sanitary butter dispenser are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents may be readily resorted to which fall within the scope of the appended claims.

Having described the invention, what is claimed as new is:

1. A sanitary butter dispensing apparatus comprising a base, said base having an upper wall, an aperture in said upper wall, a cylindrical casing rotatably mounted on said base, said casing having a lower retaining wall, said retaining wall having a plurality of openings therethrough, a plurality of butter chutes supported by said retaining wall, said chutes being in alignment with said openings, a platform positioned below said aperture in said upper wall, said openings selectively aligning with said aperture, butter cutting means carried by said upper wall, and means to rotate said casing to urge a butter stick in one of said chutes and resting on said platform to engage said butter cutting means, said last-recited means including a plunger, and a butter tray secured to said plunger for receiving pats of butter cut from a stick of butter resting on said platform, a ratchet wheel secured to said casing, a ratchet arm pivotally attached to said casing, said plunger engaging said arm and a resiliently mounted detent carried by said arm engaging said wheel to rotate said casing upon actuation of said plunger.

2. In a sanitary butter dispensing apparatus having a base, said base having an upper wall, said upper wall having an aperture, a cylindrical casing rotatably mounted on said base, said casing having a lower retaining wall, said retaining wall having a plurality of openings therethrough, a plurality of butter chutes supported by said re-

taining wall, said chutes being in alignment with said openings in said upper wall, a platform positioned below said aperture in said upper wall, said openings selectively aligning with said aperture, butter cutting means carried by said upper wall, and means to rotate said casing to urge a butter stick in one of said chutes and resting on said platform to engage said butter cutting means, said rotating means comprising a plunger, a butter tray secured to said plunger for receiving pats of butter cut from a stick of butter resting on the platform, a ratchet wheel secured to said casing, a ratchet arm pivotally attached to said casing, said plunger engaging said arm and a resiliently mounted detent carried by said arm engaging said wheel to rotate said casing upon actuation of said plunger, said plunger having pin means upwardly extending therefrom, a slot in said arm, said pin being received in said slot.

3. A sanitary butter dispensing apparatus comprising a base, said base having an upper wall, an aperture in said upper wall, a cylindrical casing rotatably mounted on said base, said casing having a lower retaining wall, said retaining wall having a plurality of openings therethrough, a plurality of butter chutes supported by said retaining wall, said chutes being in alignment with said openings, a platform positioned below said aperture in said upper wall, said openings selectively aligning with said aperture, butter cutting means carried by said upper wall, means to rotate said casing to urge a butter stick in one of said chutes and resting on said platform to engage said butter cutting means, and means carried by said upper wall to raise or lower said platform to determine the thickness of the pat of butter to be cut, said means to rotate said casing including a plunger, and a butter tray secured to said plunger for receiving pats of butter cut from a stick of butter resting on said platform.

4. A sanitary butter dispensing apparatus comprising a base, said base having an upper wall, an aperture in said upper wall, a cylindrical casing rotatably mounted on said base, said casing having a lower retaining wall, said retaining wall having a plurality of openings therethrough, a plurality of butter chutes supported by said retaining wall, said chutes being in alignment with said openings, a platform positioned below said aperture in said upper wall, said openings selectively aligning with said aperture, butter cutting means carried by said upper wall, and means to rotate said casing to urge a butter stick in one of said chutes and resting on said platform to engage said butter cutting means, and means carried by said upper wall to raise or lower said platform to determine the thickness of the pat of butter to be cut, said means to rotate said casing including a plunger, and a butter tray secured to said plunger for receiving pats of butter cut from a stick of butter resting on said platform, a ratchet wheel secured to said casing, a ratchet arm pivotally attached to said casing, said plunger engaging said arm and a resiliently mounted detent carried by said arm engaging said wheel to rotate said casing upon actuation of said plunger.

5. In a sanitary butter dispensing apparatus having a base, said base having an upper wall, an aperture in said upper wall, a cylindrical casing rotatably mounted on said base, said casing having a lower retaining wall, said retaining wall having a plurality of openings therethrough, a plurality of butter chutes supported by said retaining wall, said chutes being in alignment with said openings, a platform positioned below said

aperture in said upper wall, said openings selectively aligning with said aperture, butter cutting means carried by said upper wall, and means to rotate said casing to urge a butter stick in one of said chutes and resting on said platform to engage said butter cutting means, and means carried by said upper wall to raise or lower said platform to determine the thickness of the pat of butter to be cut, said means to rotate said casing comprising a plunger, a butter tray secured to 10 said plunger for receiving pats of butter cut from a stick of butter resting on said platform, a ratchet wheel secured to said casing, a ratchet arm pivotally attached to said casing, said plunger engaging said arm and a resiliently mounted detent carried by said arm engaging said wheel to 15 rotate said casing upon actuation of said plunger, said plunger having pin means upwardly extend-

ing therefrom, a slot in said arm, said pin being received in said slot.
